UNITED STATES PATENT OFFICE.

EDWARD B. COLBY, OF MONTCLAIR, NEW JERSEY.

DESIGN FOR A STOVE.

No. 39,595.

Specification for Design.

Patented Sept. 29, 1908.

Application filed June 27, 1908. Serial No. 440,772. Term of patent 3½ years.

To all whom it may concern:

Be it known that I, EDWARD B. COLBY, a citizen of the United States, and resident of Montclair, in the county of Essex and State of New Jersey, have invented a new, original, and ornamental Design for Stoves, of which the following is a specification.

The figure is a front elevation, in perspective, of a stove, showing my new design.

I claim:
The ornamental design for a stove, as shown.

EDWARD B. COLBY.
